(57) **CLAIM**

The ornamental design for a bone conduction earphone box, as shown and described.

DESCRIPTION

FIG. 1 is a front perspective view of a bone conduction earphone box showing my design.

FIG. 2 is a rear perspective view of the bone conduction earphone box in FIG. 1.

FIG. 3 is a front elevation view of the bone conduction earphone box in FIG. 1.

FIG. 4 is a rear elevation view of the bone conduction earphone box in FIG. 1.

FIG. 5 is a left side elevation view of the bone conduction earphone box in FIG. 1.

FIG. 6 is a right side elevation view of the bone conduction earphone box in FIG. 1.

FIG. 7 is a top plan view of the bone conduction earphone box in FIG. 1.

FIG. 8 is a bottom plan view of the bone conduction earphone box in FIG. 1; and,

FIG. 9 is a front perspective view of the bone conduction earphone box in an open configuration.

The broken lines in the drawings are employed to show portions of the bone conduction earphone box that form no part of the claimed design.

1 Claim, 9 Drawing Sheets
